(57) **CLAIM**

The ornamental design for a composite syringe, as shown and described.

DESCRIPTION

FIG. 1 is a front perspective view of a composite syringe in accordance with the new design;

FIG. 2 is a front elevation view thereof, the rear elevation view being a mirror image;

FIG. 3 is a right side elevation view thereof, the left side elevation view being a mirror image;

FIG. 4 is a top perspective view thereof;

FIG. 5 is a bottom perspective view thereof;

FIG. 6 is a top plan view thereof; and,

FIG. 7 is a bottom plan view thereof.

The rear elevational view of the new design is identical to the front elevational view thereof.

The left side elevational view of the new design is identical to the right side elevational view thereof.
